UNITED STATES PATENT OFFICE.

JOSHUA GREEN, OF HOVE, ENGLAND.

CABINET FOR CONTAINING TALKING-MACHINE RECORDS.

Application filed April 18, 1921. Serial No. 462,291.

To all whom it may concern:

Be it known that I, JOSHUA GREEN, a subject of the King of Great Britain, residing at 38 Rutland Gardens, Hove, Sussex, 5 England, have invented new and useful Improvements in and in Connection with Cabinets for Containing Talking-Machine Records, of which the following is a specification.

10 My invention relates to improvements in, and in connection with, cabinets designed for storing gramophone and like records.

The object of my invention is to provide an artistic cabinet of a shape such that it 15 occupies a minimum of floor space with a maximum of capacity and to this end, according to my invention, I make a cabinet of a cylindrical shape or a shape resembling that of a pillar or column, the diameter of 20 which is not greatly in excess of that of the records to be stored. As will be obvious a cabinet of this description can be executed in an artistic manner and occupies a relatively small space as compared with such cabinets 25 as heretofore generally made. Furthermore, my improved cabinet can be effectively constructed of ply-wood in an economical manner.

In a suitable construction of cabinet according to the invention, the body is advantageously made, as above mentioned, of 30 ply-wood which is curved to a cylindrical form so as to represent a pillar or column, the lower part of the column being furnished 35 with a basepiece, or being added to, to represent a plinth or pediment. The front half of the hollow cylinder thus formed is made in the form of two doors which are either hinged to the fixed half of the cylinder so 40 that they can be swung back or are made to slide in guides provided upon the upper and lower parts of the body.

The records are stored in a series of semi-cylindrical boxes provided with shelves or 45 the equivalent for holding the records in a horizontal position and each of which is hinged to the body in such a manner that when the records are to be stored, the said boxes are turned so that the records occupy 50 the interior of the said cylindrical body and the boxes face outwards and so that when the said boxes are swung outwards the records are exposed and can be removed as desired.

In practice, the boxes may all be mounted

upon a single pivot rod at one side of the 55 body or alternately on two rods on either side of the body.

In a modification of the invention, the cabinet may be made of the so-called elastic type, that is to say, of a series of units which 60 can be added to from time to time, as may be rendered necessary by the accumulation of records. In a cabinet of this type the units may advantageously each be made from a top and bottom disc having grooves to receive a semi-cylindrical strip of ply-wood 65 constituting the fixed portion of the body to which the doors can be attached in the described manner. A single unit can constitute a complete cabinet or a second can be superposed upon it and secured to it in any convenient manner, say, by a screw pin on the bottom of the superposed unit which engages with a screw threaded hole in the top of the lower unit; a third can be superimposed upon 70 the second and so on as may be desired.

It will be understood that a gramophone 75 may be combined with all the forms of cabinet above described. Where a gramophone is thus adapted to the cabinet it can advantageously be located in a cylindrical extension of the upper part of the body, or in a cylindrical casing pivoted axially to the cabinet by a central bolt or the like. The 80 trumpet is invisible and is formed within the said cylindrical extension or casing, and preferably around the inside of the same and so as to open on the periphery thereof, and furthermore, in practice, sliding or other doors may be provided for covering the said 85 trumpet opening when the instrument is not in use. By the use of a pivoted casing as described the trumpet opening can be directed in any required direction.

To enable the invention to be fully 90 understood, I will describe it by reference to the accompanying drawings in which:

Figure 1 is a perspective view of a gramophone combined with a cabinet for containing records therefor in accordance with the 100 invention, the doors thereof being closed.

Figure 2 is a similar view to Figure 1 but with the doors open.

Figure 3 is a sectional side elevation of the 105 cabinet and gramophone (drawn to an enlarged scale), and

Figures 4 and 5 are horizontal sections on the lines 4-4, and 5-5, Figure 3.

Figure 6 is a perspective view of one of the semi-cylindrical hinged boxes for holding the records.

Figure 7 is a perspective view similar to Figure 2 illustrating a modification.

Figure 8 is an elevation of a record cabinet of the elastic type in accordance with the invention, the doors thereof being closed.

Figure 9 is a perspective view of one of the upper sections of the cabinet with the doors open.

Figure 10 is a perspective view of the lower section thereof with the doors closed and

Figure 11 is a similar view but showing the doors open.

Referring to Figures 1 to 6, the body of the cabinet is advantageously made of plywood curved to a cylindrical form to represent a pillar or column and comprises a semi-cylindrical portion *a* connected to discs *b* and *c* at the top and bottom, respectively, the latter being preferably provided with a cylindrical casing *d* forming a plinth or 25 pediment which may be supported upon casters as indicated. *e*, *e* are the two doors forming the front and movable half of the hollow column which are preferably arranged to slide in guide grooves *f* and *g* in 30 the top and bottom *b*, *c* respectively. Or the said doors may be hinged to the fixed half *a* of the column.

h indicates the semi-cylindrical boxes for holding the records *i*, all of the said boxes 35 being hinged on a single pivot rod *j* at one side of the cabinet as illustrated in Figures 2 and 5, or alternately on two such rods as indicated in Figure 7. The said boxes are so arranged on their pivots that when turned 40 thereon into the column *a* the boxes only are exposed to view but when turned outwards the records are exposed and can be removed as required. Both these positions are indicated clearly in Figures 2 and 7. *h* indicates the shelves in the boxes *h* upon which 45 the records are supported.

The cabinet may be employed alone, or, as shown in Figures 1, 2, 3, 4 and 7, it may be combined with a gramophone. The casing *l* of this gramophone is cylindrical so as to resemble an extension of the cabinet, but is preferably pivoted centrally as at *m* to the top of the said cabinet, so that it may be turned to present the sound amplifying 50 chamber *n* in any required direction. *o*, *o* indicate a pair of doors, similar to the doors *e*, *e* for closing the mouth of the amplifying chamber *n* and *p* is a cover formed in two parts hinged together, one of which parts 55 is formed integral with the casing *l*, the said doors and cover being closed when the gramophone is not required for use.

In the modified form of cabinet illustrated in Figures 8 to 11, *q* indicates the sections 60 or units, one or more of which constitutes

or constitute the cabinet. These units are similar in construction to the cabinet illustrated in Figures 1 to 7, that is to say, each is formed of a semi-cylindrical portion *r* connected to top and bottom discs *s* and *t*, 70 and having sliding doors. One of the units is designed to stand upon the floor and is preferably provided with casters as indicated in Figure 8 and is adapted to have one or more additional units superposed upon it 75 as required, as also indicated in Figure 8. For this purpose each unit is preferably attached to the one below it by a screw pin *u* on its underside engaging a screw-threaded hole in the upper side of the said lower 80 units.

Claims.

1. In a storage cabinet for talking machine disk records the combination with a body consisting of top and bottom members, 85 a side wall having a front aperture therein, and means for closing said aperture, of a movable box adapted to pass through said aperture, supported upon a vertical pivot at one side of the front aperture in the body, 90 said box consisting of top and bottom members, forming segments of a circle and a vertical wall contiguous to the curved edges of said top and bottom members whereby the stored disks will project beyond the 95 straight edges of the top and bottom members of the movable box.

2. In a storage cabinet for talking machine disk records, the combination with a main body having a substantially cylindrical 100 chamber, provided with a front aperture in its vertical wall, of a movable box adapted to pass into said chamber through said aperture, said box consisting of top and bottom members in the form of segments of a circle, 105 and a curved vertical wall contiguous to the curved edges of said top and bottom members, and being of a curvature substantially conforming to the cylindrical wall of said cylindrical chamber, and a series of horizontal shelves, within said box of substantially the same shape as the top and bottom members, said box being pivotally connected adjacent to one end of its curved side wall, 110 to the main body at one side of front aperture, the straight edges of the top and bottom members of the box facing toward the rear of said cylindrical chamber and the curved side wall of the box substantially closing the front aperture in the main body, 115 when said box is in closed position, whereby the disks will be retained between the rear wall of the cylindrical chamber, and the curved wall of said box.

3. In a storage cabinet for talking machine disk records, a storage receptacle comprising substantially semi-circular top and bottom members a curved semi-cylindrical wall connecting the top and bottom portions adjacent to their curved edges, and 120

a plurality of substantially semi-circular shelves supported horizontally in spaced relation between said top and bottom, for supporting disks while permitting them to project from and over the straight edges of the shelves and bottom.

4. In a storage cabinet for talking machine disk records, the combination with a main body having substantially circular top and bottom members and a substantially cylindrical wall, provided with a front aperture therein, said wall having a movable portion for opening and closing said aperture, of a movable box; consisting of segmental top and bottom members, a curved side wall connecting them adjacent to their curved edges, and horizontal segmental shelves, between said top and bottom members, said box being pivoted to the main body at one end of the curved wall of said box and at one side of the front aperture in the main body, the disks being retained between the curved wall of said box and the portion of the cylindrical wall of said main body when the box is in closed position and the movable portion of the cylindrical wall of the main body when in closed position

extending over the curved wall of said box and holding the box in closed position.

5. In a storage cabinet for talking machine disk records, the combination with an enclosing casing comprising circular top and bottom members a substantially semi-cylindrical wall connecting the top and bottom members, and forming a front aperture, and movable doors for closing said front aperture and completing the cylindrical form of the casing when closed, and a plurality of boxes arranged one above the other and each supported pivotally at one side of the front aperture of the casing each of said boxes comprising substantially semi-circular top and bottom members, a substantially semi-cylindrical wall, and a plurality of substantially semi-circular shelves supported in spaced relation one above the other, said pivotal connections with each box being located adjacent to one end of the semi-circular wall thereof whereby said boxes may be independently swung into and out of the casing, and when in closed position within the casing will have their side walls at the front of the casing.

JOSHUA GREEN.
